By Attorney

UNITED STATES PATENT OFFICE.

ED L. AMUNDSON, OF HENNING, MINNESOTA.

MANURE LOADER.

Application filed May 8, 1923. Serial No. 637,589.

To all whom it may concern:

Be it known that I, ED L. AMUNDSON, a citizen of the United States, residing at Henning, in the county of Otter Tail and 5 State of Minnesota, have invented certain new and useful Improvements in Manure Loaders; and I do hereby declare the following to be a full, clear, and exact description of the invention, such as will enable others skilled in the art to which it 10 appertains to make and use the same.

The invention has for its object the provision of a machine for loading manure, compost or analogous fertilizer into a wagon 15 on whereby it is spread or supplied to the ground to be enriched.

A further object of the invention is the provision of a machine of the character aforesaid which may be readily manipulated 20 in the operation of loading, the work being performed by power derived from a motor and controlled by levers.

Other objects and advantages will be apparent and suggest themselves as the nature 25 of the invention is understood.

While the drawings illustrate an embodiment of the invention it is to be understood that in adapting the same to meet different conditions and requirements, various changes in the form, proportion and minor details of construction may be resorted to without departing from the nature 30 of the invention.

Referring to the accompanying drawings 35 forming a part of the application:

Figure 1 is a side view of a manure loader embodying the invention,

Figure 2 is a top plan view thereof,

Figure 3 is a front view,

Figure 4 a detail view of the mechanism 40 for effecting a swinging of the mast, and

Figure 5 is a detail view in rear elevation of the fork.

Corresponding and like parts are referred 45 to in the following description and designated in the several views of the drawings by like reference characters.

The numeral 1 designates the bed of a wagon which receives the parts comprising 50 the loading mechanism. A motor 2 of any preferred type is mounted upon the bed 1 and is belted or otherwise geared to the jack whereby the loading mechanism is operated.

55 A standard 3 is located at one end of

the bed 1 and is stayed at its upper end by means of brace rods 4 which extend from the upper corners of the standard 3 to the opposite end of the bed 1. An upright post 5 is pivoted to the standard 3 and a mast 6 extends outwardly from the lower end thereof and is stayed at its upper outer end by means of a brace 7 which is connected to the upper end of the standard 3. A double sheaf pulley 8 is located 60 at the upper end of the standard 3 and cables 9 and 10 pass thereover. Other sheave pulleys 11, 12 and 13 are located at intervals in the length of the mast 6, the cable 9 passing over the pulley 11 and 65 the cable 10 passing around the pulleys 12 and 13. A boom 14 pivoted to the mast 6 is provided with sheave pulleys 15 and 16, the cable 9 passing around the pulley 15 and the cable 10 passing around the pulley 70 16. A fork 17 is pivoted to the boom 14 and a sheave pulley 18 is connected thereto and receives the cable 10. The lower end of the cable 9 is attached to the fork 17. One end of the cable 10 is attached to the 75 upper end of the mast 6. The opposite end of the cable 9 is connected to a drum 20 and is adapted to wind thereon. The other end of the cable 10 is connected to a drum 19 and is adapted to wind thereon. The 80 drums 19 and 20 are loose on the respective shafts 21 and 22 and are adapted to be engaged therewith by clutch members 23 and 24 which are operable by means of levers 25 and 26. A gear wheel fast to the 85 shaft 21 is in mesh with a gear wheel 28 fast to the shaft 22. The gear wheel 28 is in mesh with a gear wheel 29 fast to a shaft 30 which is belted or otherwise geared to the motor 2. A bevel crown gear 31 90 fast to the outer end of the shaft 22 is adapted to cooperate with a double ended bevel pinion 32 slidably mounted on a shaft 34 and rotatable therewith and adapted to be shifted by means of a lever 35 where- 95 by to rotate the shaft 34 in reverse directions as required. A transverse shaft 36 is geared to the longitudinal shaft 34 and has a pinion 38 fast thereto which is in mesh with a gear wheel 39 fast to the lower 100 end of the post 5. It will thus be understood that rotation of the shaft 34 in one direction or the other effects a corresponding movement of the post 5 with the result that the mast 6 and boom 14 carried 105 110

thereby are swung laterally whereby to carry the fork 17 to and from the pile of manure to be loaded upon the wagon.

When the fork 17 is swung to the pile 5 of manure, the lever 25 is operated to throw the drum 19 into clutch engagement with the shaft 21, whereby to wind the cable 10 thereon and operate the fork 17 so as to load the same and when loaded, the lever 10 35 is operated to move the fork 17 from the pile of manure to the wagon, after which the drum 19 is released and the drum 20 thrown into clutch engagement with the shaft 22, whereby to wind the cable 9 thereon and operate the fork 17 to effect a discharge of the load into the wagon, after the operation is repeated.

What is claimed is:

1. A machine of the class described having a mast, a boom depending therefrom, a loading device extending from the boom intermediate its ends, operating cables for said loading device, pulleys on said boom on opposite sides of the loading device 25 over which the respective cables pass, one of said cables being fastened to said mast, another of said cables being fastened to said loading device, pulleys on the mast over which each cable passes, and independently 30 operable drums to control the respective cables.

2. In a machine of the character specified, a bed, a standard rising therefrom, a vertically disposed post journaled on said standard, a gear wheel at the lower end of said standard, a transverse shaft on said standard in driving relation to said gear wheel, a longitudinal shaft adjacent one side of the bed in driving relation to the transverse shaft, drums on said bed, shafts on which said drums are journaled, a driving connection between one of the last mentioned shafts and said longitudinal shaft, a mast extending from the post above the gear wheel thereof, a boom supported from the mast, a loading device supported from the boom, pulleys on the boom one on each side of said device, cables trained over said pulleys, one of said cables being fastened to said device, the other cable being fastened to said mast, pulleys on said mast on opposite sides of the cable connection thereat and over which said cables are trained, said cables being connected to said drums, and a pulley on said standard over which said cables are trained.

In testimony whereof I affix my signature in presence of two witnesses.

ED L. AMUNDSON.
